UNITED STATES PATENT OFFICE

MORRIS GORNSTEIN, OF NEW YORK, N. Y., ASSIGNOR TO UNIVERSAL FRINGE WORKS, INC., A CORPORATION OF NEW YORK

DESIGN FOR A BRAID FOR CURTAINS, LAMP SHADES, OR THE LIKE

Application filed June 19, 1929. Serial No. 31,754. Term of patent 7 years.

To all whom it may concern:

Be it known that I, MORRIS GORNSTEIN, a citizen of the United States, residing at New York, in the county of New York and State of New York, have invented a new, original, and ornamental Design for a Braid for Curtains, Lamp Shades, or the Like, of which the following is a specification, reference being had to the accompanying drawing, forming part thereof.

The figure is a face view of a piece of braid for curtains, lampshades or the like, showing my new design.

I claim:

The ornamental design for a braid for curtains, lampshades or the like, as shown.

In testimony whereof I have affixed my signature.

MORRIS GORNSTEIN.
